UNITED STATES PATENT OFFICE.

JOHN BAKER, OF BROOKLYN, NEW YORK.

BOAT-PROPELLING DEVICE.

Application filed January 6, 1925. Serial No. 866.

To all whom it may concern:

Be it known that I, JOHN BAKER, a subject of the King of Rumania, residing at Brooklyn, in the county of Kings and State 5 of New York, have invented certain new and useful Improvements in Boat-Propelling Devices, of which the following is a specification.

The present invention relates to a device 10 for propelling small boats, and aims to provide a novel and improved device having paddle wheels arranged adjacent the water line on the boat, said paddle wheels having levers positioned in the boat operatively 15 connected thereto for rotating the same.

Another object of the invention is to provide a pair of paddle wheels one arranged on each side of the boat approximately midway of the length thereof, each of said paddle wheels being adapted to be operated by 20 separate levers pivotally connected to the boat, so that said paddle wheels can be jointly or independently operated in order to properly steer the boat by the operation 25 of the paddle wheels.

A further object of the invention is to provide relatively small paddle wheels rotatably mounted on the sides of the boat at the water line thereof, said paddle wheels 30 having sprocket and chain mechanism arranged on the outside of the boat and extending downwardly from the gunwale thereof for operating the same, such structure providing a light and compact device whereby the weight thereof will not effect 35 the amount of power necessary to propel the boat.

It is also an object of the invention to provide a device of the kind indicated, 40 which is simple and substantial in construction, which can be manufactured economically, and which will be thoroughly efficient and practical in use.

With the foregoing and other objects in 45 view, which will be apparent as the description proceeds, the invention resides in the construction and arrangement of parts, as hereinafter described and claimed, it being understood that changes can be made 50 within the scope of what is claimed without departing from the spirit of the invention.

The invention is illustrated in the accompanying drawings, wherein:

55 Figure 1 is a side elevation of a small boat

showing my improved device applied thereto,

Figure 2 is a section on line 2—2 of Figure 1, and

Figure 3 is a section taken on line 3—3 of Figure 1.

Referring to the drawings, the numeral 5 indicates a boat having a bow 6, stern 7, gunwales 8, floor 9, and rear seat 10. In carrying out my invention, the numeral 11 65 designates a pair of levers pivotally connected at their lower ends, as at 12, to the floor 9 of the boat. Pivotally connected to each of said levers midway of their length, are the rear ends of connecting links 13, 70 which have their forward ends pivotally connected to the outer ends of crank arms 14 secured to and arranged for rotating the shafts 15 extending through the gunwales 8 of the boat. The shafts 15 are rotatably 75 supported at their outer ends by metallic bearings 16 arranged in the gunwales 8 and at their inner ends by brackets 17 through which said shafts extend, said brackets having depending arms 18 at 80 tached to the inner sides of the side walls of the boat.

On the outer ends of the shafts 15 and on the outside of the boat are secured large 85 sprocket gears 19 connected to small sprocket gears 20 by sprocket chains 21. The small sprockets 20 are rigidly carried by rotatable shafts 22 arranged slightly forward of the large sprockets and adjacent the water line of the boat. In order to support the shafts 22 elongated curved plates 23 are attached to the outer sides of the boat which in turn have attached at their outer ends U-shaped brackets 24 through which the outer ends of the shafts 22 extend in order to properly support said outer ends of said shafts, said shafts being supported at their inner ends by the same being received in sockets 25 provided on the plates 22. The opposite ends of the plates 100 23, brackets 24, and curved plates 26 arranged on the inner sides of the side walls of the boat are attached together by bolts 27 extending therethrough.

Attached to the outer ends of the shafts 105 22 on the outside of the U-shaped brackets 24 are blades 28 adapted to act as paddle wheels when the shafts 20 are rotated. The manner of attaching the blades 28 is by splitting the outer ends of the shafts 22 in 110

order to receive said blades in said split portions, and then passing a pin 29 through said shafts 22 and blades 28.

In operation, the party propelling the boat is seated on the rear seat 10 with each of his hands grasping one of the pivoted levers 11. By swinging said levers backward and forward the connecting links 13 and crank arms 14 will rotate the large sprocket gears carried by the shafts 15 which due to their chain connection will rotate the small sprockets 20 and consequently rotate the blades or paddle wheels 28 which are rigidly carried by the same shafts as the small sprockets. When it is desired to propel the boat in a straight, forward direction both levers are operated simultaneously, and when the boat is to be turned from its straight, forward course, the lever on the opposite side of the boat from the direction the boat is to be turned is alone operated. It can thus be seen that the operation of the levers will control the direction of the boat, as well as propel the same.

Having thus described my invention, what I claim as new is:

1. A propelling device for boats, comprising a pair of shafts pivotally supported on the gunwales of the boat, a sprocket gear carried by each of said shafts and arranged on the outside of the gunwales, a second pair of shafts one pivoted on each side of the boat adjacent the water line thereof, a second pair of sprockets one carried by each of said second mentioned shafts, chains connecting said first mentioned sprockets to said second mentioned sprockets, a paddle wheel carried by each of said second mentioned shafts, and means for rotating said first mentioned shafts for rotating said paddle wheels.

2. A propelling device for boats, comprising a pair of shafts pivotally supported on the gunwales of the boat, a sprocket gear carried by each of said shafts and arranged

on the outside of the gunwales, a second pair of shafts one pivoted on each side of the boat adjacent the water line thereof, a second pair of sprockets one carried by each of said second mentioned shafts, chains connecting said first mentioned sprockets to said second mentioned sprockets, a paddle wheel carried by each of said second mentioned shafts, a crank arm attached to each of said first mentioned shafts, a pair of levers pivotally connected to said boat at their lower ends, and a link connecting each of said levers to each of said crank arms for rotating said paddle wheels upon swinging movement of said levers.

3. A propelling device for boats, comprising a pair of shafts pivotally supported on the opposite gunwales of the boat, a sprocket gear carried by each of said shafts on the outside of the gunwales, a pair of plates one arranged upon each side of said boat adjacent the water line thereof, each of said plates having a socket provided therein, a U-shaped bracket adapted to be attached to each of said plates at the opposite ends of said brackets, a second pair of shafts one arranged upon each side of said boat and each having one end thereof pivotally supported in said sockets on said plates while the opposite end thereof is pivotally supported by the shafts passing through the U-shaped brackets, a second pair of gears one arranged upon each of said second mentioned shafts between said plates and U-shaped brackets, chains connecting said first mentioned sprockets to said second mentioned sprockets, a paddle wheel carried by each of said second mentioned shafts on the outside of said U-shaped brackets, and means for rotating said first mentioned shafts for rotating said paddle wheels.

In testimony whereof, I have affixed my signature.

JOHN BAKER.
